UNITED STATES PATENT OFFICE.

FELIX LYDE AMES, OF EASTBOURNE, ENGLAND.

BERTH FOR SHIPS.

No. 878,852.

Specification of Letters Patent.

Patented Feb. 11, 1908.

Application filed January 4, 1906. Serial No. 294,610.

To all whom it may concern:

Be it known that FELIX LYDE AMES, a subject of the King of Great Britain, residing at Fairburn, Willingdon Road, Eastbourne, in the county of Sussex, England, gentleman, has invented certain new and useful Improvements in and Relating to Berths for Ships, of which the following is a specification.

10 This invention relates to berths for ships, and has for its object to render berths or bunks more comfortable and to afford increased convenience to passengers while enabling the berths or bunks to occupy the 15 minimum amount of space.

According to my invention the berth or bunk comprises a frame or tray suitably supported by props or legs and adapted to carry a mattress which may be of the usual 20 spring or other character; the frame being provided with side and end flaps or trays adapted for employment as hereinafter described.

In order that the said invention may be 25 clearly understood and readily carried into effect I will proceed to describe the same with reference to the accompanying drawings in which:—

Figure 1 represents a side view of a berth 30 or bunk constructed according to my invention. Fig. 2 is a corresponding plan and Fig. 3 a transverse section taken along the line $x-x$ in Fig. 1.

The berth or bunk comprises a frame a 35 having a mattress b attached to or supported thereon. The frame is formed or provided with an upwardly extending side c and a head piece d ; pillars or uprights being arranged as at e for supporting a side flap f .

40 This side flap may be formed in sections hinged or otherwise suitably connected and when in the position shown in full line in the drawings, the said flap may be secured in such position by bolts indicated at f' f' .

45 This side flap thus serves to protect the occupant of the bunk or berth and prevent the occupant from falling out. Or the said flap may be arranged so as to serve as a seat at the side of the bunk or berth as indicated 50 in broken lines in Fig. 3, the portion f^x which is the outer portion of the said flap, or its upper portion when in its vertical position serving as the seat. A stop f^z is provided on the underside of the innermost flap so as to

prevent the total withdrawal of the flap 55 from the guides a^x in or beneath the frame or tray a . When not required for protection or for a seat as hereinbefore described the whole of the aforesaid flap portion f may be concealed by bringing the same from its vertical to a horizontal position and then pushing the same into the frame or tray a . When used as a seat the outermost section of the flap near to the point where it is hinged to the inner section takes a bearing on the adjacent part of the frame or tray. The said outwardly extending portion of the flap f may however be supported upon a trestle or trestles or other suitable structure or structures. The head piece d may if desired be 65 arranged similarly to the side flap f . The end g of the berth is arranged in such a manner that it may either form a folding end piece to afford protection in cold weather or it may form a seat or a table for toilet or 75 other uses. This end g may be composed of a flap, hinged at g' and provided with hinged legs g^2 , connected with the said flap by a folding strut g^3 so that, when the flap is turned into a vertical position to protect the 80 occupant of the berth, the legs may lie snugly against the outer surface of the flap and so occupy very little space. If desired the space between the legs g^2 may be filled in with paneling and when assuming the 85 position shown in dotted lines in Fig. 1 it may serve for toilet or any other desired use. The table may be formed by securing in a horizontal position across the legs a tray or flat surface preferably of wood, additional 90 trestles or other convenient devices being employed as desired for supporting the said tray or surface. The bunk or berth may be suitably upholstered or portions may be padded and cushions or other articles may 95 be provided as may be necessary or desirable and according to the requirements or the taste or fancy of the occupant.

At the head portion of the bunk or berth there may be provided a drawer or tray h 100 adapted to receive articles of food, drink, medicine. To render the articles on the said tray readily accessible to the occupant of the bunk or berth the side piece i of the bunk is suitably shaped at the upper edge to permit 105 the occupant to readily reach any articles deposited on the said tray h .

By means of this invention, there may be

combined in one bunk or berth, trays for food or other articles, protection against the effects of rough weather, seats and tables, all of which are readily accessible to and capable of easy manipulation by the occupant.

Where the cabin wall forms one side of the bunk or berth, it is obvious that the side devices will be applied to the side remote from such wall. The bunk or berth may if desired, be constructed in sections for convenience in packing for transport or other purposes.

What I claim and desire to secure by Letters Patent of the United States is:—

- 15 1. In a bunk or berth, a mattress-supporting frame having an upwardly extended side and head piece, a sectional side flap foldable beneath the mattress frame and uprights for supporting said flap and between which it is retained in vertical position.
- 20 2. In a bunk or berth, a mattress-supporting frame having an upwardly extended side and head piece, a sectional side flap foldable beneath the mattress frame, uprights for supporting said flap and between which it is retained in vertical position and locking means for said flap when in its vertical position.
- 25 3. A bunk or berth having a hinged side slidably foldable beneath the berth and a

hinged end, said side being in movably united sections.

4. In a bunk or berth, a frame having guides beneath the same, a movable flap in hinged sections adapted to slide within said guides and to be concealed beneath said frame and uprights between which said flap is held when in distended vertical position.

5. In a bunk or berth, a mattress-supporting frame having guides beneath the same, a movable flap in hinged sections adapted to slide within said guides and to be concealed beneath said frame, and a stop to prevent complete withdrawal of said flap from the guides.

6. In a bunk or berth, the combination of a mattress-supporting frame, uprights on said frame, a side flap of hinged sections cooperating with said uprights, a guide for said flap beneath said frame, a stop to prevent the complete withdrawal of said flap, and means for securing said flap, when in its vertical position, to said uprights.

In testimony whereof I have hereunto set my hand in presence of two subscribing witnesses this eighteenth day of December 1905.

FELIX LYDE AMES.
